(Continued)*Primary Examiner* — Cathron C Brooks*Assistant Examiner* — Christian P. McLean(74) *Attorney, Agent, or Firm* — Sterne, Kessler, Goldstein & Fox P.L.L.C.(57) **CLAIM**

The ornamental design for a display screen or portion thereof with graphical user interface, as shown and described.

DESCRIPTION

FIG. 1 is a front view of a display screen or portion thereof with graphical user interface showing the claimed design; and,

FIG. 2 is another front view of the design of FIG. 1, shown in a different broken line environment.

The outermost broken lines in the figures show a display screen or portion thereof, and form no part of the claimed design. The other broken lines in the figures show portions of the graphical user interface that form no part of the claimed design.

1 Claim, 2 Drawing Sheets**Related U.S. Application Data**

continuation of application No. 29/616,004, filed on Sep. 1, 2017, now Pat. No. Des. 820,300, which is a continuation of application No. 29/567,732, filed on Jun. 11, 2016, now Pat. No. Des. 796,547.
